COMBINED CHAIR AND HAIR DRYER

Frederic Weinberg, 1514 W. Chew Ave., Philadelphia, Pa.

Filed Jan. 30, 1963, Ser. No. 73,371

Term of patent 14 years

(Cl. D15—3)

FIG.1

FIG. 2

FIG. 6

FIG. 3

FIG. 4

FIG. 5

FIG. 7

FIG. 1 is a perspective view of a combined chair and hair drier showing my design;

FIG. 2 is a front elevation view of the combined chair and hair drier shown in FIG. 1;

FIG. 3 is a rear elevational view of the combined chair and hair drier shown in FIG. 1;

FIG. 4 is a side elevation view of the combined chair and hair drier taken from one side thereof;

FIG. 5 is a side elevational view of the combined chair and hair drier taken from the other side thereof;

FIG. 6 is a top plan view of the combined chair and hair drier; and

FIG. 7 is a bottom plan view of the combined chair and hair drier.

I claim:

The ornamental design for a combined chair and hair drier, substantially as shown.
